CLAIM

The ornamental design for a corner air purifier unit, as shown and described.

DESCRIPTION

Corner air purifier unit

1.1: Perspective

1.2: Front

1.3: Back

1.4: Left

1.5: Right

1.6: Top

1.7: Bottom

(Continued)

The claimed design is for a corner air purifier unit. The broken lines shown in the figures represent portions of the corner air purifier that form no part of the claimed design.
